BRITISH WEST INDIES.

NON-REFILLABLE BOTTLE.

988,061.

Specification of Letters Patent. Patented Mar. 28, 1911.

Application filed August 28, 1909, Serial No. 515,347. Renewed October 4, 1910. Serial No. 585,306.

To all whom it may concern:

Be it known that I, CHARLES E. W. ARCHER, a subject of the King of Great Britain, residing at Port of Spain, Trinidad, British West Indies, have invented new and useful Improvements in Non-Refillable Bottles, of which the following is a specification.

This invention relates to non-refillable bottles designed to contain perfume, toilet preparations, powders or other material, and one of the principal objects of the same is to provide reliable and efficient means whereby the discharge orifice of the material may be opened or closed and in which after the original contents of the bottle have been used the bottle cannot be again filled.

Another object of the invention is to provide a non-refillable bottle in which the bottle proper is formed of a shape to provide two separate and distinct compartments, one of said compartments having a neck in which is fitted a valve and a stopper, said stopper being provided with discharge orifices and a cover which may be rotated to open and close the orifices, said valve and cover being connected to the mouth of the bottle in a manner to prevent refilling of the same after the original contents have been exhausted.

These and other objects may be attained by means of the construction illustrated in the accompanying drawings, in which,—

Figure 1 is a detail sectional view taken through the upper end of the bottle neck, and showing the stopper, the valve and the cover in place. Fig. 2 is a top plan view of the cover rotated to expose the discharge openings. Fig. 3 is a top plan view of the hollow glass stopper removed from the bottle. Fig. 4 is a transverse sectional view on the line 8—8 of Fig. 1. Fig. 5 is a similar view on the line 9—9 of Fig. 1. Fig. 6 is a detail perspective view of the metal cap of the stopper. Fig. 7 is a similar view of the cover. Fig. 8 is a perspective view of the holding sleeve for connecting the parts to the stopper.

Referring to the drawings, the container neck 16 is provided at its mouth portion with a series of threads 17 formed in its inner wall. Fitted into the upper end of the neck is a stopper 18 preferably formed of glass or other vitreous material, said stopper being provided with exterior screw threads 19 to engage the screw threads 17 at the upper end of the neck. The stopper 18 is provided

with a surrounding bead 20, and to hold the stopper in place in the bottle neck headless screws 21 extend through the neck and through the threaded portion of the stopper, said screws terminating flush with the outer and inner walls of the neck and stopper. The stopper 18 is provided with a curved or dome shaped top 22 having a central opening 23 and a series of perforations 24 at one side thereof. A cap 25 provided with a central perforated boss 26 and a cut-away portion 27 is placed upon the top or dome 22 of the stopper with the cut-away portion coincident with the perforations 24 in said stopper. Superposed upon the cap 25 is a cover 28 having a recess 29, a central opening 30 and a peripheral bead 31, said cover being fitted upon the cap 25 with the peripheral bead 31 engaging the bead 20 of the stopper and arranged thereon to bring the recess 29 into coincidence with the perforations 24 in the stopper. For holding the cover 28 in place a metal collar 32 is provided, said collar having an interiorly grooved bead 33 upon its upper edge, said bead inclosing the bead 31 in the cover 28 and the sleeve 32 surrounding the bottle neck and covering the screws 21 which secure the stopper against rotation in the bottle neck.

Extending through the central opening 30 in the cover and through the opening *a* in the boss 26 and through the opening 23 in the stopper 22 is a valve stem 34, said valve stem having a washer or shoulder 35 to bear upon the upper side of the stopper 22, and said stem having an enlarged upper portion 36 which terminates in a milled button or head 37 for convenient operation of the stem, said head being secured to the stem by means of a screw 38, and said stem being connected to the boss 26 by a screw or pin 39 extending through the boss 26 and through said enlarged portion 36 of the stem. The lower end of the stem is provided with an enlarged portion 40 having a threaded end and fitted with a nut 41. A valve seat 42 comprising a disk having oppositely disposed openings 43 therethrough and an extended hub or boss 44 is connected inside the stopper 22 by peripheral screw threads engaging similar threads formed in the interior wall of the lower end of the stopper. The enlarged portion 40 of the stem extends through a central opening 45 in the valve seat, and the nut 41 is fitted 110

upon the end of said stem to hold the parts in adjusted position.

5 A combined valve and baffle 46 provided with a central elliptical or other form of opening 47 is disposed upon the top of the valve seat 42 to cover the openings 43 therein, said valve having upwardly projecting fingers 48 to serve to limit the movement of the valve toward the top 22 of the stopper 10 upon the inversion of the bottle, and thereby prevent said valve from sealing or partly sealing the perforations 24 in said top. The stem 34 extends through the opening 47, as shown in Fig. 1.

15 From the foregoing it will be obvious that the container being filled before the stopper is placed in position, as shown in Fig. 1, the contents of the bottle may be dispensed through the discharge perforations 24 after 20 the cap 25 has been rotated to bring the opening 27 into coincidence with the cut-away portion 29 of the cover 28 and the perforations 24 in the stopper. When not in use, the cap 25 is rotated to close the discharge 25 opening in the stopper and to prevent escape of volatile liquids or the deterioration of the contents. When it is desired to dispense the liquid or powder in the container, by rotating the cap 25 to expose the discharge 30 openings 24, the bottle is tilted and the contents passed through the openings 43 in the valve seat, and the valve 46 is moved away from the seat upon one side to permit the liquid or powder to pass through the opening 35 47 and from thence out through the perforations 24. When the container is righted up the valve 46 drops back in its position upon the valve seat 42, thus serving to practically seal the stopper to cut off communication 40 between the bottle and the discharge perforations.

My invention is comparatively simple in construction, is reliable and efficient in use, can be connected to any form of bottle, can 45 or container and provides reliable means to prevent refilling of the container after the original contents have been dispensed.

I claim:—

1. A non-refillable bottle comprising a

neck, a stopper fitted into the neck and provided with discharge perforations, a rotatable cap fitted to the stopper and provided with a recess adapted to be brought into coincidence with the discharge perforations, a stem connected to the cap, an apertured valve seat secured within the stopper, and a valve loosely supported upon the seat, said stem extending through the valve and seat and provided with a nut for securing the parts in place. 50

2. A non-refillable bottle or container comprising a neck, a stopper secured in said neck and provided with discharge perforations, a rotatable cap, a stem connected thereto, a valve seat in the stopper, and a valve provided with projecting fingers and an enlarged central opening. 60

3. In a non-refillable bottle, the combination of a stopper rigidly secured at the mouth of the neck of the bottle and provided with discharge perforations, a cap mounted to rotate upon the stopper to cover the perforations and to expose the same for discharging the contents of said bottle, a valve seat within the stopper, and a valve having projecting fingers and a central opening, said valve being loosely mounted within the stopper to drop by gravity to its seat and to move to a position to discharge the contents when the bottle is tilted. 80

4. A non-refillable bottle comprising a neck, a stopper in the neck, said stopper provided with perforations, a cap fitted to the stopper and provided with a cut-away portion, a cover fitted to the stopper and provided with a recess, means for rotating the cap, a valve seat within the stopper and a gravity valve provided with an enlarged central opening and fingers to prevent said valve sealing the perforations upon the inversion of the bottle. 85

In testimony whereof I affix my signature in presence of two witnesses.

CHARLES E. W. ARCHER.
